AUTOMATIC VOLUME CONTROL IN VOICE
FREQUENCY CIRCUITS

Elwyn Tudor Jones, Eltham, London, England, assignor, by mesne assignments, to International Standard Electric Corporation, New York, N. Y., a corporation of Delaware

Application December 8, 1943, Serial No. 513,369
In Great Britain April 9, 1943

8 Claims. (Cl. 179—84)

1

This invention relates to circuits for the operation of a signal receiving device by signal currents of a predetermined frequency lying within the voice frequency range whilst preventing its operation by unwanted currents, also lying within this same range of frequencies, both types of currents being supplied to the device from a single communication channel.

There are various limiter circuits known in the art which limit by chopping the peaks of the currents under control. The present invention makes use of automatic volume control instead of a limiter circuit, and this former device provides several advantages. Unlike limiter circuits the automatic volume control may be adjusted to cause the peaks in unwanted speech currents to depress the average speech currents which may reach the signal receiving device to a low value for a considerable length of time and in addition the same circuit provides a substantially constant level of the desired signalling currents without distorting the wave form thereof. This results in more reliable operation over a wide range of signal input levels because the low harmonic content of such non-distorted signal currents reduces filter losses and makes possible the design of simpler and more effective guard circuits, which prevent operation of the receiving device, which may be a relay when certain frequencies are present on the communication level.

According to the present invention a circuit of the kind set forth above comprises a variable transducer, a filter passing signal frequencies and excluding frequencies outside the signal range and a signal receiving device connected together in series and a circuit for automatically varying the amplitude of the currents passed by said transducer in inverse proportion to the amplitude of the currents at the input of said filter, this inverse proportion being modified by means acting to neutralize the amplitude control when the energy of the input currents falls below a predetermined reference level, this reference level being either constant, or being made to vary when the signal current of predetermined modulation frequency is present upon the communication channel.

The nature of the invention will be better understood from the following description taken in conjunction with the accompanying drawings in which:

Fig. 1 shows a circuit according to the invention using a variable attenuator;

Fig. 1A shows a modification of the circuit of Fig. 1; and

Fig. 2 shows the circuit of Fig. 1 with an additional amplitude control.

Referring to the drawings, Fig. 1 shows a circuit for the operation of a signal device X by currents in the voice frequency range connected

2

at the terminals 1, 2 to a circuit over which both speech currents and signalling currents pass.

The circuit comprises a variable attenuator VA, an amplifier A and a filter F in series. The attenuator and amplifier together constitute the transducer. Two diagonal points of a rectifier bridge R are connected to the secondary of a transformer L3 which forms part of the filter F, and the two opposite diagonal points are connected to the signal device X. This device may be of any suitable type, as used in the telecommunication art. The filter comprises inductances L1, L2, L3 shunted by condensers C1, C2, C3. The loss in the attenuator VA is controlled by a current derived from the amplified currents and passing through a rectifier W1. The automatic volume control is prevented from acting below a certain minimum amplitude of received currents by an opposing voltage V, acting through a rectifier W2, a condenser C4 being inserted to isolate this opposing voltage from the amplifier A and filter F. A condenser C5 is used to maintain the automatic volume control in action over a predetermined period of time, as is usual.

25 The filter F is designed to pass frequencies intended to operate the signal device X and the tuned circuits L1, C1 and L2, C2 are preferably tuned to frequencies outside that range. These circuits thus cause the filter F to present a high impedance to frequencies outside the signalling range.

30 This provides an effective and economic guard circuit, since the high impedance of the filter to frequencies outside the signalling range increases the relative voltage magnification at such frequencies at the filter input and thus causes these frequencies to exercise an accentuated effect in increasing the loss through the attenuator. In addition or as an alternative to this arrangement of the impedance of filter F,

35 the effect of unwanted frequencies in the automatic volume control circuit may be accentuated by placing in front of the attenuator an equalising network, EN, which, paradoxical though it may appear, is arranged to cause greater loss to signal frequencies than to unwanted frequencies and in particular to pass with small loss unwanted frequencies close to the signal frequency and harmonics of the signal frequency. This arrangement is shown in Fig. 1A. The operation 40 of the equalizing network is similar to that of the filter in that the network tends to provide unwanted signals at the output of the amplifier which are greater in amplitude than the desired signal. Since the automatic volume control circuit operates on the difference in signal levels, it 45 may be adjusted to provide attenuation to the unwanted signals so that they are reduced to the same level resulting with the filter alone. When the filter and the equalizing networks are used 50 together their effects are additive.

Because the automatic volume control does not chop the peaks of the signalling currents it is well suited for use with modulated (including interrupted) carrier signalling currents since it provides volume control without loss of percentage modulation so that reliable functioning is possible over a wide range of input levels.

At the same time, the circuit may, as shown in Fig. 2, be used to provide a still further means of obtaining immunity from false operation by speech by utilising the modulation of signalling currents to that end.

In Fig. 2, the signalling device X is connected in the same manner as in Fig. 1. The rectified currents passing the rectifier bridge R will include the modulation frequency in addition to the carrier frequency and condensers C6 and C7 and resistance R6 are connected across the device X to separate out the modulation frequency and apply it to a transformer T1. This frequency, after passing through T1, is rectified in the voltage doubling network R1 and the resulting rectified current is applied to the control of the variable attenuator VA in opposition to the normal control circuit. In this way all currents will be reduced to a low value except a properly modulated signal of the right carrier frequency. Such a signal will produce a neutralising current and will rise to a high level and will operate the signal device X.

When current derived from transformer T1 is rectified, the resultant direct current voltage will vary as a function of the energy content of the modulation of the signal. Therefore the reference level below which energy derived via C4 can function to effect control of the variable attenuator will be raised during the persistence of such modulation currents, due to the increased value of the neutralizing current. This causes the attenuator to deliver maximum energy to the succeeding elements of the system, thereby operating signal device X so as to bring about the maximum effective sensitivity thereof.

What is claimed is:

1. A circuit for the operation of a receiving device by signal currents within the voice frequency range whilst preventing its operation by unwanted currents comprising a variable transducer, a filter passing signal frequencies and excluding frequencies outside the signal range and a signal receiving device connected together in series and a circuit for automatically varying the amplitude of the currents passed by said transducer in inverse proportion to the amplitude of the currents at the input of said filter, above a predetermined minimum reference level.

2. A circuit as claimed in claim 1 comprising means for automatically maintaining the amplitude of currents passed by said transducer at a value determined by a peak of received energy for a period of time.

3. A circuit as claimed in claim 1 in which said filter presents to said transducer such an impedance for frequencies outside the signal range as to accentuate the effect of the presence of said frequencies in reducing the amplitude of currents passed by said transducer.

4. A circuit as claimed in claim 1 in which said transducer is preceded by an equalising network causing greater loss at signal frequencies than at unwanted frequencies.

5. A system for operating a receiving device by signal currents within a desired frequency range but not by currents of frequencies outside said range, said system comprising a transducer

whose transmission efficiency may be varied, a filter connected to receive signals from said transducer and to pass only the desired frequency range, said receiving device being connected to receive signals from said filter, and an automatic volume control circuit responsive to the amplitude of signals at the input of said filter for varying the transmission efficiency of said transducer in inverse relation to the amplitude of said current, above a predetermined minimum reference level.

6. A system for operating a receiving device by signal currents within a desired frequency range but not by currents of frequencies outside said range, said system comprising a transducer having a variable transmission efficiency, a filter connected to receive energy from the output of said transducer and to pass only the desired frequency range, said receiving device being connected to receive signals from the output of said filter, and an automatic volume control circuit adapted to receive energy from a position between said transducer and said filter, said automatic volume control circuit including elements for developing a voltage responsive to the energy impressed on said volume control circuit and varying the transmission efficiency of said transducer in inverse relation thereto, above a predetermined minimum reference level.

7. A system for operating a receiving device by signal currents within a desired frequency range but not by currents of frequencies outside said range, said system comprising a transducer having a variable transmission efficiency, a filter connected to receive energy from the output of said transducer and to pass only the desired frequency range, said receiving device being connected to receive signals dependent on the output of said filter, an automatic volume control circuit responsive to the amplitude of energy at a point between said transducer and said filter, and a second volume control circuit responsive to energy at said receiving device, said second volume control circuit being connected in opposition with the first mentioned volume control circuit, and a connection from said volume control circuits to the transducer for varying the transmission efficiency of said transducer in inverse relation with the energy derived from said first volume control circuit, above a level determined by the energy derived from said second volume control current.

8. A system according to claim 7 in which the second volume control circuit comprises circuit elements for separating from the signal at said receiving device, currents having the frequency of signal modulation, rectifying said currents and applying said last-mentioned rectified currents in opposition to the energy derived by said first mentioned volume control circuit, whereby the reference level of the point whereat said first volume control becomes effective is varied to accord with the value of said currents of signal modulation frequency.
